Primary Examiner — Barbara Fox*Assistant Examiner* — Jamaal Rasheed(74) *Attorney, Agent, or Firm* — Cochran Freund & Young LLC; William W. Cochran(57) **CLAIM**

The ornamental design for a multi-directional plume, as shown and described.

DESCRIPTION

FIG. 1 is a top isometric view of a multi-directional plume.

FIG. 2 is a front view of the multi-directional plume.

FIG. 3 is a right side view of the multi-directional plume.

FIG. 4 is a left side view of the multi-directional plume.

FIG. 5 is a top view of the multi-directional plume.

FIG. 6 is a bottom view of the multi-directional plume; and,

FIG. 7 is a rear view of the multi-directional plume.

Any broken line portions of the disclosure are for illustrative purposes only and form no part of the claimed design.

1 Claim, 7 Drawing Sheets(56)
